(57) **CLAIM**

The ornamental design for ferrule holder for optical fiber connectors, as shown and described.

DESCRIPTION

1. Ferrule holder for optical fiber connectors

1.1 : Perspective

1.2 : Front

1.3 : Back

1.4 : Top

1.5 : Bottom

1.6 : Left

1.7 : Right

1.8 : Cross sectional

1.9 : Cross sectional

Name of this industrial design product: Ferrule holder for optical fiber connectors; Reproduction 1.1 is a perspective view showing the front, bottom, and left side of the design; Reproduction 1.8 is a cross-sectional view along line A-A' of reproduction 1.4; Reproduction 1.9 is a cross-sectional view along line B-B' of reproduction 1.2; The dash-dash broken lines in the reproductions form no part of the claimed design; The dash-dotted broken lines define the boundaries of the claim and form no part of the claimed design.
